DESIGN FOR A BICYCLE

Ohmer E. Stutsman and George L. Becker,
Dayton, Ohio

Application December 21, 1933, Serial No. 50,180

Term of patent 7 years

To all whom it may concern:

Be it known that we, OHMER E. STUTSMAN and GEORGE L. BECKER, citizens of the United States of America, residing at Dayton, in the county of Montgomery, State of Ohio, have invented a new, original, and ornamental Design for a Bicycle, of which the following is a specification, reference being had to the accompanying drawing, forming a part thereof.

Figure 1 is a plan view of a bicycle with a part of the handle bar broken away for convenience in illustration, showing our new design.

Figure 2 is a side elevational view thereof.

The dotted lines in Fig. 2 show the contour of an insert in the body which may be used when the bicycle is ridden by a man, but which may be removed when the bicycle is ridden by a woman.

The dominant feature of the design resides in the particular contour of the body of the bicycle.

We claim:

The ornamental design for a bicycle as shown and described.

OHMER E. STUTSMAN,
GEORGE L. BECKER,
